UNITED STATES PATENT OFFICE.

IRA T. McCREADY, OF OAK PARK, ILLINOIS.

CORK-TAPERING MACHINE.

1,116,830.

Specification of Letters Patent.

Patented Nov. 10, 1914.

Application filed October 9, 1906. Serial No. 338,188.

To all whom it may concern:

Be it known that I, IRA T. McCREADY, a citizen of the United States, residing at Oak Park, in the county of Cook and State of Illinois, have invented certain new and useful Improvements in Cork-Tapering Machines, of which the following is a specification.

My invention relates to that general class 10 of machines known as cork tapering machines and the object of my present invention is to provide a simple and efficient machine so constructed and arranged as to be capable of a greater output than machines 15 of this character heretofore used and also automatic in every respect from the feeding of the corks to the discharge thereof from the machine in completed condition.

The principal feature of my invention, 20 and one which results in its rapid operation and increased output, resides in the provision of a novel centering device by which each cork is in its turn centered as received from a feed chute and then moved bodily 25 with said centering device to the chucks and held thereby while being presented to the knife for the purpose of being tapered.

According to my construction and arrangement, the cork is properly centered at 30 all speeds of the machine and under all conditions, inasmuch as the centering device, which receives and determines the proper position of the cork, is itself movable bodily toward and away from the chucks, with the 35 result that no opportunity exists for any rotation or displacement of the cork during its transfer to the chucks. In connection with or as a coöperating part of the centering device, I also employ a back piece or plate to 40 form a stop or abutment for the cork and its delivery to the chuck and to assist in or assure of the centering of the cork, which plate is made movable to coöperate with the main centering device and so that it may be withdrawn 45 slightly from the cork to give it clearance during and after the cutting operation, and to permit the cork to drop after being released from the chucks.

Other features of advantage and utility of 50 my present machine will be apparent from the description hereinafter given.

In the drawings Figures 1 and 2 are different side elevations of my new machine; Fig. 3 a plan view thereof; Fig. 4 an elevation of a portion of the machine shown in

Fig. 1 but made on a somewhat larger scale; Fig. 5 a sectional elevation on the line 5—5 of Fig. 7; Fig. 6 a sectional elevation on the line 6—6 in Fig. 7; Fig. 7 a plan view indicated by the line 7—7 and the arrow in Fig. 6 but showing a portion of the knife in dotted lines; Fig. 8 a sectional detail on the line 8—8 of Fig. 6; Fig. 9 a perspective of the lower end of the feed tube or chute; Fig. 10 a vertical sectional elevation on the line 10—10 of Fig. 1 looking in the direction of the arrow, and Fig. 11 a vertical sectional elevation on the line 11—11 of Fig. 1 looking in the direction of the arrow.

Referring to the present embodiment of 70 my invention as illustrated in Figs. 1, 2 and 3, the same comprises a suitable frame 1, in which is mounted a vertical shaft 2 which carries near its upper end the usual circular knife 3. The shaft is driven in suitable 75 manner as by a pulley 4 arranged near its lower end, and, as usual in machines of this character, the knife shaft is movable vertically at intervals and at the proper time in the operation of tapering the corks, as hereinafter explained. A cross plate 5 is secured to the main frame and arranged at an angle to the horizon and consequently at an angle to the horizontal knife 3, such angle corresponding to the usual or standard taper 80 of cork. Upon this cross plate is formed a bearing 6 for a driving shaft 7, which is itself driven by means of a belt or rope 8 running over a small pulley or sheave 9 on the shaft 7 and over a larger pulley or sheave 90 10, on a cross shaft 11, driven by the gear 12, as hereinafter explained. This cross piece also supports a bearing 13 in which rotates 85 an arbor 14, whose inner end is serrated and formed as a chuck to engage the cork and cause it to be rotated in the manner hereinafter made apparent, Figs. 4 and 7. While this arbor and its chuck may, of course, be continuously driven if desired, yet in the present instance it is intermittently operated. 90 As shown, this arbor is driven by means of a clutch, one member 15 of which is the stationary member and secured to the arbor 14, whereas the other member 16 is the movable member and is driven by the shaft 7, as 105 clearly indicated in Figs. 1, 3 and 4. This clutch is under the control of a shifter 17, coöoperating with the movable clutch member and having a rod or bar 18 extending obliquely across the machine and fulcrumed 110

at its rear end to the machine frame at the point 19, Figs. 2, 3 and 10. Intermediate its length this bar carries a depending cam roller 20, which is adapted to coöperate with a cam 21 formed on or secured to the inner side or face of the pulley or sheave 10. As a result of this construction and arrangement, it is obvious that at the proper intervals of time the movable member of the 10 clutch is shifted positively into and out of engagement with the stationary clutch member, so that at corresponding intervals the arbor or chuck 14 will be rotated and stopped alternately. The movable clutch 15 member is held toward a disengaged position with a yielding pressure in suitable manner, as by means of a spring 22, Fig. 3 and consequently the cam moves the clutch shifter positively against the tension of such 20 spring.

Coöoperating with the chuck 14, which engages one end of the cork, is a center 23 adapted to engage and grip the other end thereof. This center 23 is in alinement 25 with the chuck, Figs. 3 and 4, and has a slight reciprocating movement so that it is adapted to engage and hold the corks during the cutting operation, at which time the corks are rotated by the positively 30 driven chuck or chuck member 14, and to release such corks after such cutting operation is completed. In the present instance the center 23 is arranged on the inner end of a spring-pressed reciprocable rod 24 having 35 bearings 25 formed on or secured to the cross plate or piece 5. This rod is inwardly pressed with a yielding pressure by means of the coiled spring 26, which bears against a collar 27 at one end and 40 against the outer bearing 25 at the other end. The center 23 is by preference offset from the longitudinal axis of the rod 24 and is moreover, readily detachable from the inner end of such rod in any suitable 45 manner, so that such device may be readily removed and another one substituted either of the same size or of a different size for accommodating corks of different diameter or length. For giving this rod the proper 50 reciprocating movement against the tension of its spring 24, that is for removing the center 23 from engagement with the cork, I provide a suitable operating connection which, in the present instance, comprises a 55 lever 28 pivoted intermediate its length on the stud 29 on the cross plate 5 and pivotally connected at its upper end to said rod and carrying at its lower end a cam roller 30, which is interposed in the path of movement of a cam 31. This cam is carried at one end of the main driving shaft 32, Figs. 1, 3 and 4, which shaft is provided with the tight and loose pulleys 33, 33 and also with a bevel gear 34 for driving the gear 12 and 60 cross shaft 11 hereinbefore referred to.

The corks *a* are fed in automatic manner from a suitable source of supply and through a chute or feed tube 35, such corks being fed end to end in endless succession and being delivered by the chute upon a 70 bodily movable centering device at a point adjacent the cork-holder, said feed chute terminating in a stationary table 35^a formed below the inclosing plate 35^b, which is supported by rod 35^c on a side plate 35^d itself supported by the angle plate 35^e forming a stationary table. This table may be a separate piece as shown or the end of the feed chute or tube itself flattened out as a table and the same is supported by the 75 rod 35^f which is secured to the transverse bar 35^g. The corks are fed downwardly from the chute and the outermost is forced by the gravity or pressure of the row of corks, across said table and upon the horizontal movable table or plate 36 of a rock arm 36^a, Figs. 3, 5, 6, 7 and 9. This movable table or plate has a substantially horizontal motion inwardly and outwardly for the purpose of transferring the corks bodily 80 and presenting the same to the cork-holder in position to be caught and held thereby in the cork-tapering operation without any liability whatever of disturbing their proper position or alinement during the 85 transferring operation. In presenting the cork to the cork-holder the movement of said table 36 is inwardly, that is to the right, and after the cork has been engaged thereby such table moves in the opposite 90 direction to initial position in order to receive and center the next succeeding cork, repeating the cycle of movement described, see Fig. 5. In order to properly center the cork I provide said centering device with 95 an adjustable finger or block 37 rising above the plane of the table or plate 36, in position to engage the body of the cork, and forming with said table a V-shaped recess 100 37^a in which the cork is centered. This block is held in adjusted position by the thumb-nut 36^a. To limit the outward movement of the cork delivered from the feed chute and about to be operated upon I provide an adjustable gage 38 carried on the 105 upper end of an upright rod or support 39 (whose lower portion 39^a is here shown of the larger diameter) and adjustable toward and away from the end of the cork-chute through the medium of the lateral 110 rod 40, which passes through the upper end of the support 39. To prevent any possible displacement of the cork upon said table after being delivered thereto, I provide a yielding or spring finger 41 which is adjustably supported by the gage 38 through the medium of the transverse pin 42 and supporting piece 43, adjustably connected to the stop plate, as clearly illustrated in 115 Figs. 6 and 7. This spring finger is curved 120 45 to the right and is so arranged that it will 125 support the cork as it is being tapered and 130 will not interfere with the centering block 37.

downwardly in a position to engage the inner side of the cork and to overcome any tendency of the cork to become displaced. The cork is delivered by said shifting centering device against the back piece or plate 44 which forms part of the centering device and is mounted upon a rock arm 45. This rock arm is secured to a rock shaft 46 operated at the proper time by operating connections hereinafter referred to. This centering plate, which is illustrated in detail in Figs. 5 to 8, is adjustably mounted upon its rock arm 45 in suitable manner, but in the present instance the same is provided at its lower end, Figs. 6 and 8, with a laterally extending portion or block 47, which is received in a horizontal slot 48 near the upper end of the rock arm. This block is engaged by an adjusting screw 49 bearing at one end against the outer face of the rock arm, with the result that the plate may be adjusted horizontally by rotating the adjusting screw in one direction or the other as required.

The plate is maintained in adjusted position by the nut 50 engaging a screw-threaded projection 51 on the block and bearing against the sides of the rock arm. This plate is made adjustable so as to provide for corks of different diameters, the object thereof being to coöperate with the main centering device to insure the proper centering of the cork so that when the latter is positioned against said plate the longitudinal axis of the same coincides exactly with the longitudinal axis of the chuck arbor. The object of mounting this plate on a movable member or rock arm is to provide for the shifting of the plate away from the cork immediately after the chucks have taken hold of the cork, with the result that the plate will not interfere with the rotation of the cork, especially in case such cork has inequalities upon its sides, but will afford clearance and will permit the cork to drop after the cutting operation.

The rock shaft 46 may be rocked in any suitable manner, but in the present instance this shaft, which is mounted in the bearings 52 52 in the cross piece 5 is provided with a depending arm 53, Figs. 1, 2, 4, and 10 in position to be contacted and operated by means of an arm 54 secured to a rock shaft 55. As shown in Fig. 10, the cam 54 does not contact the arm 53 directly but through the medium of the adjustable set screw 54^a whereby the movement of the parts may be more accurately timed. This latter rock shaft is the shaft on which the rock arm 36^a is mounted, with the result that the centering plate 44 is moved up to position at the instant when the rock arm 36^a and its plate 36 are moved inwardly to deliver the cork. This rock arm 37 is held to its outward position shown in Fig. 5 with a yielding pressure, as by means of a coiled spring 56

around said rock shaft 55. For rocking this latter shaft, I provide the same with an inwardly extending arm 57, shown in detail in Figs. 5, 6 and 11 and in general in Fig. 3, which arm is arranged in the path of movement of a long operating bar or arm 58 extending across the machine and pivoted at the rear side thereof in the lugs 59. This operating bar or arm 58 has at a point intermediate its length a cam roller 58^a which bears upon a cam 60 secured to the cross shaft 11, with the result that during the rotation of the cross shaft the operating bar 58 is alternately raised and lowered and with the further result that the rock shaft 55 and the associated parts are correspondingly rocked. This rock shaft is stopped or limited in one direction by contact of the stop arm 55^a against the set screw 55^b in frame 5.

In practice, the corks are fed automatically through the feed chute and are forced across the stationary table 35^a which is in reality the delivery end of said chute, directly onto the table of the main centering device, which, as hereinbefore described, is movable bodily toward the cork-holder. Each cork is, in its turn, centered in the V-shaped recess 37^a of the centering device and the proper centering is further assured by means of the centering plate 44. These two parts of the centering device move in opposite directions and toward and away from each other, the main centering device moving at a greater speed than the centering plate 44, so that when these two parts of the centering device reach or substantially reach their limit of movement toward each other, the longitudinally movable center 23 forces the cork against the positively driven chuck 14, with the result that the cork is rotated and during such rotation is operated upon by the circular knife 3 in the well known way. After the two parts of the centering device have accomplished their centering action and the cork-holder has engaged the cork, the back piece or centering plate 44 moves back sufficiently to give clearance between itself and the cork and thereby prevent any interference with the cutting operation or operations of the machine and permitting the cork to readily drop in to the delivery pipe or chute 61 after the cutting operation is completed. It is thus evident that the corks are fed from a magazine or feed chute directly into a centering device or movable part thereof, which part moves as a whole, the corks being moved into properly centered position while out of contact with any relatively stationary part of the machine, so that the corks are properly centered and are transferred to and engaged by the cork-holder in such position. It will be understood that by preference the shavings resulting from the cut

ting operation are removed by means of a blower 62 arranged above the knife, as seen in Figs. 2 and 5.

As hereinbefore stated, the table 36 is adjustable on the rock arm 36^a on which the desired adjustment is obtained in the present instance as clearly indicated in Figs. 5 and 6 by the provision of the adjusting screw 87 which is arranged to engage a block or projection 88 extending from the arm 36 into a slot 89 in the upper end of said rock arm. By turning the adjusting screw 87 in one direction or another the table 36 is raised or lowered, as the case may be, and such adjusted position is maintained by means of the thumb screw 90.

As hereinbefore stated the knife 3 is mounted upon the vertical shaft 2 which is driven by the pulley 4. The lower end of this shaft bears upon an adjustable shoe 91 movable upon the upwardly extending flanges 92^a of a beam 92 which is pivoted at one end at 93 to the main frame of the machine, as clearly shown in Fig. 1. For raising and lowering this beam 92 and consequently raising and lowering the knife I provide a vertical rod 94 pivotally connected to an arm 94^a which is secured to a rock shaft 94^b having mounted thereon intermediate its length a lifter arm 94^c which in its rocking movements is adapted to contact and operate said beam 92. For operating the rod 94 I provide an inverted U-shaped cam bar 95 pivoted at one end to the main frame at 95^a, the other end of this cam bar being operatively connected with the vertical rod 94. At the middle of its U-shaped portion this bar is provided with a cam roller 96 which is adapted to be contacted by the cam 97 which is mounted upon the cross shaft 11, all as clearly indicated in Fig. 11. In the rotation of said shaft this bar 95 is raised and lowered and through the connections already described the knife 3 is correspondingly raised and lowered.

I claim:

1. In a cork-tapering machine, the combination with a cutting disk arranged to rotate in a horizontal plane, a cork-holding device comprising separable chucks, a blank-feeding chute, an oscillating horizontally movable table at one side of the chucks and on to which the blanks are successively fed from said chute, a horizontally movable back plate at the opposite side of the chucks, and means for moving said table and back plate horizontally toward and away from each other and toward and away from the chucks, said table and back plate forming and having means for centering and positioning the blank accurately with respect to the chucks.

2. In a cork tapering machine, the combination, with the cutting knife and with cork-holding mechanism, of a device for first centering the corks and subsequently pre-

senting them thereto comprising a table which is movable toward and away from such mechanism, and stationary means for engaging the cork with a yielding pressure while on said centering device and during the movement of the table toward the cork-holding means.

3. In a cork tapering machine, the combination, with the cutting knife and cork holding mechanism, of means for centering the corks and presenting them thereto comprising a table which is movable toward and away from such mechanism, and means for engaging the cork with a yielding pressure during its transfer to the cork-holding mechanism consisting of a spring finger arranged in the path of movement of the cork and adapted to contact the same in its said shifting movement, said finger being stationary and permitting the cork to slip thereunder in its transferring movement.

4. In a cork tapering machine, the combination, with the cutting knife and cork holding mechanism, of means for centering the corks and presenting them thereto comprising a table which is movable toward and away from such mechanism, and means for engaging the cork with a yielding pressure consisting of an adjustable spring finger normally in fixed position and arranged in the path of movement of the cork in the said shifting thereof to the cork holding mechanism.

5. In a cork tapering machine, the combination, with the cutting knife and cork holding mechanism, of means for centering the corks and presenting them thereto comprising an oscillating table which is movable toward and away from such mechanism, means for automatically feeding the corks one at a time upon the table, and an independently movable back piece or plate which co-operates with said centering means and against which the corks are shifted thereby.

6. In a cork tapering machine, the combination, with the cutting knife and cork holding mechanism, of means for centering the corks and presenting them thereto comprising a table which is movable toward and away from such mechanism, means for automatically feeding the corks upon the table at one side thereof, and a movable back piece or plate which co-operates with said centering means and against which the corks are shifted thereby, said centering means and plate being movable toward and away from each other.

7. In a cork tapering machine, the combination, with the cutting knife and cork holding mechanism, of means for centering the corks and presenting them thereto comprising a table which is movable toward and away from such mechanism, and a back piece or plate which co-operates with said

centering means and against which the corks are shifted thereby, said plate being movable to and from operative position and being adjustable as to such operative position to afford earlier or later contact with the cork.

8. In a cork tapering machine, the combination, with the cutting knife and cork holding mechanism, of means for centering 10 the corks and presenting them thereto comprising a table which is adapted to receive the corks one at a time and which is movable toward and away from such mechanism, a plate against which the corks are 15 shifted one at a time and means whereby such plate is swung away from the cork immediately prior to the cutting operation to afford clearance between itself and the cork.

9. In a cork tapering machine, the combination, with the cutting knife and cork holding chucks, of means for centering the corks and presenting them thereto comprising a table which is adapted to receive the corks one at a time and which is movable 25 toward and away from such chucks, a plate against which the corks are shifted one at a time, and which has a movement opposite to that of the centering means, and a rock arm on which the plate is mounted.

- 30 10. In a cork tapering machine, the combination, with the cutting knife and cork holding chucks, of means for centering the corks and presenting them thereto comprising a table which is adapted to receive the 35 corks one at a time and which is movable toward and away from such mechanism, a plate against which the corks are shifted one at a time, and which has a movement opposite to that of the centering means, a 40 rock arm on which the plate is mounted, and means for adjusting the plate with respect to the arm, said gage being stationary and independent of the table.

11. In a cork tapering machine, the combination with the cutting knife and cork holding mechanism, of means for centering the corks before presenting them to said mechanism comprising a table which is adapted to receive the corks one at a time, 45 and which is movable toward and away from such mechanism, a back piece or plate which coöperates with said centering means and against which the corks are shifted, and means for moving said centering means 50 and the plate toward and away from each other but at different speeds.

12. In a cork tapering machine, the combination, with the rotatable cutting knife, of means for holding the cork in the cutting 60 operation, a centering device on which the cork is centered preliminarily to its presen-

tation to the holding means, and which is movable bodily toward such holding means to present the cork thereto in properly centered position, said device including an oscillating table and a block thereon for engaging the cork, and means for automatically feeding corks to said table comprising an inclined chute terminating in a flat portion adjacent said table and at one side and 65 on a level therewith whereby the corks are fed upon the table by gravity, and a gage for limiting the feed of the cork across the table, said gage being stationary and independent of the table. 75

13. In a cork tapering machine, the combination, with the rotatable cutting knife, of means for holding the cork in the cutting operation, a centering device on which the cork is centered preliminarily to its presentation to the holding means, and which is movable bodily toward such holding means to present the cork thereto in properly centered position, said device including an oscillating table and a block thereon for engaging the cork, and means for automatically feeding corks to said table comprising an inclined chute terminating in a flat portion adjacent said table and at one side and 80 on a level therewith whereby the corks are fed upon the table by gravity, a stationary gage for limiting the feed of the cork across the table, and a stationary yielding means interposed in the path of movement of the cork for pressing it against said 85 block on the oscillating table. 90

14. In a cork tapering machine, the combination, with the rotatable cutting knife, of means for holding the cork in the cutting operation, a centering device on which the 100 cork is centered preliminarily to its presentation to the holding means, and which is movable bodily toward such holding means to present the cork thereto in properly centered position, said device including an oscillating table and a block thereon for engaging the cork, and means for automatically feeding corks to said table comprising an inclined chute terminating in a flat portion adjacent said table and at one side and 105 on a level therewith whereby the corks are fed upon the table by gravity, a stationary adjustable gage for limiting the feed of the cork across the table, and an adjustable spring finger interposed in the path of movement of the cork for pressing it against said 110 block on the oscillating table. 115
